INTERNAL-COMBUSTION ENGINE

Application filed February 23, 1928. Serial No. 256,210.

This invention relates to internal combustion engines and refers more particularly to sleeve valve and like types of engines. In this general class of engines it is customary to provide a cylinder head or other structure spaced within the cylinder to form a pocket receiving one or more sleeve valves. In certain well known types of sleeve valve engines such as the Knight or the Burt-McCollum for example, the sleeve ports are moved into the sleeve pocket usually during the firing of the charge whereby the sleeve ports are cooled. It is known that the sleeve pocket tends to accumulate what is generally known as "sludge," being in the nature of carbon, oil, residue constituents of the intake and exhaust gases, and the like. It has heretofore been necessary to periodically remove the sludge accumulation by dismantling the cylinder head and scraping away the deposit since the accumulation interferes with the proper operation of the sleeve valves, produces overheating in the region of the sleeve pocket, and otherwise interferes with the desired efficient and smooth running qualities of the engine.

I have invented means for removing the matter which finds its way to the sleeve pocket. If such matter is removed periodically it may be disposed of without difficulty according to my invention, preferably before any great accumulation is experienced in the sleeve pocket. When permitted to accumulate this matter is acted upon by the heat of the engine and in time carbonizes and becomes heavily incrusted in the sleeve pocket. My invention provides for periodically removing the sludge by means preferably automatically responsive to operation of the engine whereby the sleeve pocket will be maintained substantially free from the objectionable deposits. I prefer to provide suction means acting periodically as aforesaid as I have found that in general a suction when applied constantly to the sleeve pocket tends to produce an undue accumulation of sludge in the pocket whereas a periodic suction does not in this respect appreciably alter the normal operating conditions of the engine.

Referring to the accompanying drawings illustrating one embodiment of my invention,

Fig. 1 is a sectional elevation view through one of the engine cylinders and along 1-1 of Fig. 3, the sleeve valve nearing the completion of its intake cycle, 55

Fig. 2 is a view generally corresponding to Fig. 1 and along 2-2 of Fig. 4, the sleeve valve having completed its intake cycle, 60

Figs. 3 and 4 are diagrammatic developments of the sleeve and cylinder ports and associated parts, the sleeve position respectively corresponding to Figs. 1 and 2. 65

In the drawings I have shown, for illustrating my invention, a sleeve valve engine of the Burt-McCollum type in which a ported single sleeve valve has a combined reciprocating and oscillating movement producing the valving functions of the engine 70 as generally well known in the art. Thus the cylinder A formed in cylinder block A' has intake and exhaust ports 10 and 11 respectively, the sleeve valve B having intake ports 12 and exhaust ports 13 respectively co-operating with the corresponding cylinder ports. Any well known or suitable mechanism (not shown) may be employed for moving the sleeve in the customary path 14, for example, any point on the sleeve such as 75 the point 15 moving in such path. 80

The cylinder head B closes the cylinder, being provided with a re-entrant or depending portion 16 spaced within the cylinder end to provide an annular pocket 17 of suitable capacity to accommodate the number of sleeve valves employed and the movement thereof. 85

In order to effect the removal of matter tending to accumulate in the pocket 17 as aforesaid, I have provided one or more conduits suitably positioned so as to communicate with the sleeve pocket and with one or more of the sleeve intake ports during at least a portion of the intake cycle whereby the suction produced by the usual engine piston reciprocating within the sleeve will effect a suction in the sleeve pocket. Thus the cylinder 17 may be formed with a conduit 18 suitably located with respect to a sleeve intake port 12 so as to establish the desired suction in the 95 100

sleeve pocket. Thus in Figs. 1 and 3 the intake cycle is nearing completion, (the usual piston nearing the suction stroke), the sleeve pocket 17 being in communication with the working chamber 19 of the engine by reason of the conduit 18 and port 12. The sleeve valve continuing its travel as indicated by the arrow on the valve path 15 moves the ports 12 out of communication with the ports 10, for compression, (the usual piston nearing its upward compression stroke). The sleeve at this time for the usual four stroke cycle occupies the position shown in Figs. 2 and 4. In these figures the ports 12 are spaced above the bottom edge of the cylinder head and consequently sealed against escape of gases to the pocket 17, a sealing ring 20 when desired further sealing the pocket. Any leakage past the sleeve valve to the sleeve pocket will be removed by suction to the engine working chamber, this suction in the present embodiment of my invention, acting once for each cycle of the engine. During the compression, working, and exhaust strokes of the engine the conduit 18 is free from communication with the working chamber 19 as will be readily apparent from the valve diagrams in Figs. 3 and 4.

While I have illustrated my invention in connection with the single sleeve Burt-McCollum type of engine, it will be apparent that the teachings of my invention are also adaptable to advantage in other types of sleeve valve engines, or in engines having sleeve or generally similar pockets tending to accumulate objectionable matter. Other modifications of my invention will also suggest themselves and it is not my intention to limit my invention except as specifically set forth in the appended claims.

What I claim as my invention is:

1. In an engine of the sleeve valve type, a cylinder providing a working chamber, sleeve valve means associated with the cylinder, a sleeve pocket structure accommodating the sleeve valve means, a conduit communicating with the sleeve pocket, and means periodically producing a suction in said conduit, said sleeve pocket being free from communication with the working chamber during the working stroke of the engine.

2. In an engine of the sleeve valve type, a cylinder providing a working chamber, sleeve valve means associated with the cylinder, a sleeve pocket structure accommodating the sleeve valve means, a conduit communicating with the sleeve pocket, and means controlled by the sleeve valve means for periodically producing a suction in said conduit, said sleeve pocket being free from communication with the working chamber during the engine working stroke.

3. In an engine of the sleeve valve type, a cylinder providing a working chamber, sleeve valve means associated with the cylinder, a

sleeve pocket structure accommodating the sleeve valve means, a conduit communicating with the sleeve pocket, and means responsive to operation of the engine for producing a suction at intervals in said conduit, said sleeve pocket being free from communication with the working chamber during the engine working stroke. 70

4. In an engine of the sleeve valve type, a cylinder providing a working chamber, sleeve valve means associated with the cylinder, a sleeve pocket structure accommodating the sleeve valve means, a conduit communicating with the sleeve pocket, and means responsive to operation of the engine for producing a suction in said conduit during one cyclical event of each cycle of engine operation, said sleeve pocket being free from communication with the working chamber during the remaining cyclical events. 75

5. In an engine of the sleeve valve type, a cylinder, sleeve valve means associated with the cylinder, a sleeve pocket structure accommodating the sleeve valve means, and means including a conduit for periodically placing the sleeve pocket in communication with the engine working chamber. 80

6. In an engine of the sleeve valve type, a cylinder, sleeve valve means associated with the cylinder, a sleeve pocket structure accommodating the sleeve valve means, and means including a conduit for periodically placing the sleeve pocket in communication with the engine working chamber during at least a portion of the engine intake. 85

7. In an engine having a working chamber, a cylinder having an intake port, sleeve valve means ported to control communication between the cylinder intake port and working chamber, a sleeve pocket structure for the sleeve valve means, and means establishing communication between the sleeve pocket and the engine working chamber only when the cylinder intake port is in communication with the working chamber. 90

8. In an engine of the sleeve valve type, a cylinder, sleeve valve means associated with the cylinder, a sleeve pocket structure accommodating the sleeve valve means, a conduit communicating with the sleeve pocket, and means producing a suction in said conduit only during at least a portion of the engine intake. 95

9. In an engine having a working chamber, a cylinder having an intake port, at least one sleeve valve having an intake port controlling the cylinder intake port, a pocket structure for the sleeve valve spaced above said cylinder intake port, and means effective when the working chamber is in communication with the cylinder intake port for establishing communication directly between the sleeve valve intake port and the sleeve pocket. 100

10. In an engine, a cylinder, valve means controlling the engine intake and exhaust, a

- chamber cooperating with the valve means, and suction means periodically acting to remove sludge accumulations from the valve chamber.
11. In an engine, a cylinder ported for intake and exhaust, a sleeve valve having a combined reciprocating and oscillating movement and ported for cooperation with the cylinder ports, a cylinder head closing the cylinder end and having a portion depending within the cylinder to provide a pocket accommodating the upper end of the sleeve valve, and means controlled by the sleeve valve for removing sludge from said pocket. 5
12. In an engine, a cylinder ported for intake and exhaust, a sleeve valve having a combined reciprocating and oscillating movement and ported for cooperation with the cylinder ports, a cylinder head closing the cylinder end and having a portion depending within the cylinder to provide a pocket accommodating the upper end of the sleeve valve, a conduit communicating with said pocket, and means controlled by said sleeve valve for producing a suction in said conduit. 10
13. In an engine, a cylinder ported for intake and exhaust, a sleeve valve having a combined reciprocating and oscillating movement and ported for cooperation with the cylinder ports, a cylinder head closing the cylinder end and having a portion depending within the cylinder to provide a pocket accommodating the upper end of the sleeve valve, and a conduit communicating with said pocket and with a port of said sleeve valve during at least a portion of the engine intake. 15
14. In an engine, a cylinder, a sleeve valve, a sleeve pocket, said cylinder and sleeve valve having cooperating intake and exhaust ports, and a conduit communicating with the pocket and with one of said sleeve ports when the latter is in registration with its cooperating cylinder port. 20
15. In an engine, a cylinder, a sleeve valve, a sleeve pocket, said cylinder and sleeve valve having cooperating intake and exhaust ports, and a sludge removing conduit communicating with the pocket and with the sleeve intake port when the latter is in registration with its cooperating cylinder intake port. 25
16. In an engine of the sleeve valve type, a cylinder providing a working chamber, sleeve valve means associated with the cylinder, a sleeve pocket structure accommodating the sleeve valve means, a sludge conducting conduit communicating with the sleeve pocket structure, and means causing periodic removal of sludge from the sleeve pocket structure through the said conduit, said sleeve valve means shielding said conduit against entry thereinto of the fuel mixture during compression thereof in the working chamber. 30
17. In an engine of the sleeve valve type, a cylinder providing a working chamber, sleeve valve means associated with the cylinder, a sleeve pocket structure accommodating the sleeve valve means, a sludge conducting conduit communicating with the sleeve pocket structure, and means responsive to and during running of the engine for causing periodic removal of sludge from the sleeve pocket structure through the said conduit, said conduit being shielded against entry thereinto of the fuel mixture during compression thereof in the working chamber. 35
18. In an engine of the sleeve valve type, a cylinder providing a working chamber, sleeve valve means associated with the cylinder, said cylinder provided with an intake port and an exhaust port controlled by said sleeve valve means, a sleeve pocket structure accommodating the sleeve valve means, and means including a conduit communicating with the sleeve pocket constructed and arranged to remove sludge accumulations from the sleeve pocket, said conduit being free from communication with the working chamber during at least a portion of each cycle of engine operation. 40
19. In an engine, a cylinder providing a working chamber, valve means controlling the intake to and exhaust from said chamber respectively, a pocket cooperating with the valve means and protected against communication with the working chamber during the engine working stroke, and suction means periodically acting to remove sludge accumulations from the pocket. 45
20. A sleeve valve engine comprising in combination, a cylinder providing a working chamber, sleeve valve means within the cylinder, a cylinder head depending within the sleeve valve means and providing a sleeve pocket, a piston within the sleeve valve means, said sleeve pocket being free from communication with the working chamber during the working stroke of the engine, a cylinder intake port spaced axially of the cylinder from the sleeve pocket controlled by the sleeve valve means for introducing fuel mixture directly from the cylinder intake port into the working chamber, and means whereby the sleeve pocket is placed in communication with the working chamber during the suction stroke of the piston. 50
21. A sleeve valve engine comprising in combination, a cylinder providing a working chamber, sleeve valve means within the cylinder, a cylinder head depending within the sleeve valve means and providing a sleeve pocket, a piston within the sleeve valve means, said sleeve pocket being free from communication with the working chamber during the working stroke of the engine, a cylinder intake port controlled by the sleeve valve means for introducing fuel mixture di- 55
- 60
- 65

rectly from the cylinder intake port into the working chamber, and means whereby the sleeve pocket is placed in communication with the working chamber during a portion only of the engine intake.

22. A sleeve valve engine comprising in combination, a cylinder providing a working chamber, sleeve valve means within the cylinder, a cylinder head depending within the sleeve valve means and providing a sleeve pocket, a piston within the sleeve valve means, said sleeve pocket being free from communication with the working chamber during the working stroke of the engine, a cylinder intake port controlled by the sleeve valve means for introducing fuel mixture directly from the cylinder intake port into the working chamber, and means whereby the sleeve pocket is placed in communication with the working chamber during the suction stroke of the piston, said sleeve pocket being otherwise closed.

23. A sleeve valve engine comprising in combination, a cylinder providing a working chamber, sleeve valve means within the cylinder, a cylinder head depending within the sleeve valve means and providing a sleeve pocket, a piston within the sleeve valve means, said sleeve pocket being free from communication with the working chamber during the working stroke of the engine, a cylinder intake port controlled by the sleeve valve means for introducing fuel mixture directly from the cylinder intake port into the working chamber, and means whereby the sleeve pocket is placed in communication with the working chamber during a portion only of the suction stroke of the piston, said sleeve pocket being otherwise closed.

24. A sleeve valve engine comprising in combination, a cylinder providing a working chamber, sleeve valve means within the cylinder, a cylinder head depending within the sleeve valve means and providing a sleeve pocket, a piston within the sleeve valve means, said sleeve pocket being free from communication with the working chamber during the working stroke of the engine, a cylinder intake port controlled by the sleeve valve means for introducing fuel mixture directly from the cylinder intake port into the working chamber, and means whereby the sleeve pocket is placed in communication with the working chamber during only the latter portion of the suction stroke of the piston.

25. A sleeve valve engine comprising in combination, a cylinder providing a working chamber, a sleeve valve means within the cylinder, a cylinder head depending within the sleeve valve means and providing a sleeve pocket, a piston within the sleeve valve means, said sleeve pocket being free from communication with the working chamber

during the working stroke of the engine, a cylinder intake port controlled by the sleeve valve means for introducing fuel mixture directly from the cylinder intake port into the working chamber, and means whereby the sleeve pocket is placed in communication with the working chamber during only the latter portion of the suction stroke of the piston, said sleeve pocket being otherwise closed.

26. A sleeve valve engine comprising in combination, a cylinder providing a working chamber, sleeve valve means within the cylinder, a cylinder head depending within the sleeve valve means and providing a sleeve pocket, a piston within the sleeve valve means, said sleeve pocket being free from communication with the working chamber during the working stroke of the engine, cylinder intake and exhaust ports arranged substantially in a common plane perpendicular to the cylinder axis, and means placing the sleeve pocket in communication with the intake chamber during the suction stroke of the engine.

27. A sleeve valve engine comprising in combination, a cylinder providing a working chamber, sleeve valve means within the cylinder, a cylinder head depending within the sleeve valve means and providing a sleeve pocket, a piston within the sleeve valve means, said sleeve pocket being free from communication with the working chamber during the working stroke of the engine, cylinder intake and exhaust ports arranged substantially in a common plane perpendicular to the cylinder axis, and means placing the sleeve pocket in communication with the intake chamber during the suction stroke of the engine, said sleeve pocket being otherwise closed.

28. A sleeve valve engine comprising in combination, a cylinder member providing a working chamber sleeve valve means therein, a cylinder head member depending within the cylinder member to provide a sleeve pocket accommodating the sleeve valve means, cooperating intake porting means for the cylinder member and sleeve valve means, and means including the intake porting means of the sleeve valve means for placing the sleeve pocket in communication with the working chamber during the piston suction stroke, said sleeve pocket being otherwise closed.

29. A sleeve valve engine comprising in combination, a cylinder member providing a working chamber, sleeve valve means therein, a cylinder head member depending within the cylinder member to provide a sleeve pocket accommodating the sleeve valve means, cooperating intake porting means for the cylinder member and sleeve valve means, a conduit provided by one of said members opening at one end thereof into the sleeve pocket and having its other end positioned

for registration with the intake porting means of the sleeve valve means during the piston suction stroke.

In witness whereof, I hereunto subscribe my name this 16th day of February, A. D. 5 1928.
